UNITED STATES PATENT OFFICE.

CHARLES W. GRAHAM, OF CRESTWOOD, NEW YORK, ASSIGNOR TO AMERICAN CAN COMPANY, OF NEW YORK, N. Y., A CORPORATION OF NEW JERSEY.

CAN-END-SEAMING DEVICE.

1,262,327.

Specification of Letters Patent.

Patented Apr. 9, 1918.

Application filed March 15, 1916. Serial No. 84,352.

To all whom it may concern:

Be it known that I, CHARLES W. GRAHAM, a citizen of the United States, residing at Crestwood, in the county of Westchester and 5 State of New York, have invented certain new and useful Improvements in Can-End-Seaming Devices, of which the following is a specification.

The invention relates to the hermetic 10 sealing of cans of the so-called sanitary type, without the use of solder for the attachment of the end parts; and has for its objects to improve the perfection of the hermetic joint or seam by which the top end or cover is 15 united to the can body; to simplify the preliminary partial assemblage of the parts; and to make the final sealing operation more simple and free from mistake. To these ends the invention comprises a can body 20 having an outstanding peripheral flange around its mouth, and a packing, such for instance as a paper ring-liner, fixed on said flange so as to be fed with the can body, and to be stationary therewith during the sealing 25 operation, the flange and ring-liner being adapted to be infolded with the cover flange in a known manner to form a hermetic double or equivalent seam. Moreover the outer peripheral edge of the packing is in- 30 closed by a rim flange formed on the peripheral edge of the can body flange, which rim flange is turned up and inward so as to overlie and confine the packing and effect- 35 ually prevent it being lost or displaced at any time before the can closing operation. The said flanged can body and packing constitute a sealing element or unit which is or may be supplied to packers for use with any suitable and corresponding top end or cover.

40 Advantages attendant on this improvement are that it is practically insured that no can shall be closed without a packing in the closure seam, also it is desirable that the packing be free with respect to the cover and 45 not partake of any rotary movement of the same which may be imparted by the seaming head, but remain fixed with respect to the can flange; whereby the cover may turn smoothly on the packing and the latter will 50 not be abraded, cut or crumpled by being rubbed against either the outer or the inner edge of the can body flange, or against the surface thereof, which is ordinarily not so smooth as the face of the cover, and by this

improvement the packing is related to the 55 can body as desired and is more fully protected against any cutting, abrasion or displacement by the closing operation.

With such objects in view, as well as other 60 advantages which may be incident to the use of the improvements, the invention consists in the parts and combinations thereof hereinafter set forth and claimed, with the understanding that the several necessary elements constituting the same may be varied 65 in proportions and arrangement without departing from the nature of the invention.

In order to make the invention more clearly understood there is shown in the accompanying drawings means for carrying 70 the same into practical effect, without limiting the improvements, in their useful applications, to the particular constructions which, for the purpose of explanation, have been made the subject of illustration. In 75 the said drawings:

Figure 1 is a top plan view of a flanged can body, and a packing, embodying the invention, the cover being indicated in dotted lines.

Fig. 2 is a vertical section of the upper 80 end of the same, with the top separated therefrom, on a larger scale.

Fig. 3 is a similar view of the can, showing the first operation of sealing and illus- 85 trating how the flexible liner is protected from abrasion or displacement as the double seaming is started.

Fig. 4 is a similar view showing the double seam completed into a hermetic seal. 90

Referring to the drawings, 1 is the can body formed at its mouth with an outstanding peripheral flange 2. This flange is suitable to be interfolded with a corresponding flange 3 of a top end or can cover 4 in a 95 known manner and by automatic machinery to form a hermetic sanitary closure, with the aid of the interposed packing or ring liner 5. Such cover is preferably formed with a central depression or shoulder 6 100 adapted to fit the interior of the can mouth, and with a depending lip or curl 7 at the extremity of the flange 3.

This ring-liner or its equivalent is fixed on the body flange 2 before the body is fed 105 to the closing station. This is done by having the ring-liner terminate a little inside of the can body flange 2, and by form-

ing on the said flange, before or after the application of the liner, a rim flange 8 which overlies the outer margin of the ring-liner.

This form of sealing element, comprising 5 the flanged can body and the attached and marginally inclosed packing, gives the result of a hermetic closure when the cover is seamed thereto, with the additional advantage before mentioned.

10 When the seaming devices first come into operation, they may cause a rotation of the cover on the can body and ring-liner, as the cover bears on, or mainly on, the rim flange 8, and by the time that the cover is compressed tightly on the ring-liner it ceases 15 to rotate under the influence of the seaming devices. The ring-liner is thus protected and its integrity maintained so that it performs its proper function as an element of the hermetic seal.

Also in the act of forming the well known double seam, the liner is effectively protected at its outer edge from abrasion or displacement caused by the edge of the 25 body flange rubbing against the inner surface of the cover flange during the early stages of starting the double seam. Where the liner is placed in the cover flange it sometimes happens that the edge of the body 30 flange seizes the yielding surface of the liner and tends to push it outward into the curl of the cover flange, just as the bending, due to forming the seam, begins; this action displaces the liner from its normal concentric 35 position and produces a seam of doubtful quality.

The lip or curl 8 in this invention, absorbs all abrasion due to bending or forming the seam and holds the liner in exactly 40 the right position to form a hermetic joint.

The lip 8 of the body flange may change the final shape of the double seam from that usually employed, by producing a shoulder 45 9 around which the cover flange may be formed. I have illustrated this changed form in Fig. 4.

What is claimed is:

1. A sheet metal can body having a flange extending outwardly from said body and formed with an upwardly and inwardly turned edge and adapted for double seaming with a can end, said flange being nearly enough horizontal for the purpose of double seaming, and having thereon a ring-like packing which is held in place by the upwardly and inwardly turned edge of said flange. 50

2. A sheet metal can body having a flange extending outwardly from said body and formed with an upwardly and inwardly turned edge and adapted for double seaming with a can end, said flange having thereon a ring-like packing the outer margin of which is inclosed by the upwardly and inwardly turned edge of said flange, 65 and the inner margin of which terminates outside of the vertical face of the can body which is to fit against the corresponding face of the can end.

3. In a sanitary can seal comprising 70 flanged body and end elements doubled seamed together, gasket material applied on the top of the flange of the body element, the edge of said body element being bent prior to the double seaming operation upwardly and inwardly over a portion of said gasket material. 75

4. In a sanitary can seal comprising flanged body and end elements double seamed together, gasket material applied 80 between the inner and main portions of the flanges of said elements near to the bases of both of said flanges and to the can body wall and directly on that one of said elements which is interior in the seam and is 85 inclosed by the other element, the edge of said interior element being bent prior to the double seaming operation upwardly and inwardly over a portion of said gasket material. 90

In testimony whereof I affix my signature.
CHARLES W. GRAHAM.
